ATTORNEY.

UNITED STATES PATENT OFFICE.

JOHN J. RATTIGAN, OF HOMESTEAD, PENNSYLVANIA.

METHOD OF ATTACHING LIPS TO DREDGE-BUCKETS.

1,377,925.

Specification of Letters Patent. Patented May 10, 1921.

Application filed May 24, 1919. Serial No. 299,442.

To all whom it may concern:

Be it known that I, JOHN J. RATTIGAN, a citizen of the United States of America, residing at Homestead, in the county of Allegheny and State of Pennsylvania, have invented certain new and useful Improvements in Methods of Attaching Lips to Dredge-Buckets, of which the following is a specification.

10 My present invention relates to a method of repairing the wearing-lips of manganese steel buckets and particularly such buckets as used on sand dredges, and furnishes the means of extending the life of such dredge buckets almost indefinitely. Another object of the present invention is to provide a dredge bucket having the parts which receive the "wear" by contact with a hard gritty material such as sand, and also the 15 parts which resist the shock when the buckets encounter boulders or rocks concealed in the sand, made of manganese steel, while the body section of the bucket which does not receive such severe treatment in service, is 20 constructed of ordinary cast or alloyed steel. The cost of manufacture of the buckets can be in this way very greatly reduced while their efficiency is maintained. These and other features of the present invention will 25 be more fully explained as the description proceeds hereinafter in this specification.

In the accompanying drawings forming part of this specification, I have shown one complete example of my invention and some 30 modifications thereof, constructed according to the best mode I have so far devised for the practical application of the principles of my invention.

Figure 1 is a central vertical section 40 through a dredge-bucket.

Fig. 2 is a face view of the rear portion of a bucket taken in the direction of the arrows 2-2 of Fig. 1.

Fig. 3 is a plan view on line 3-3 of 45 Fig. 1.

Fig. 4 is a side elevation of an apparatus devised for use in carrying out my invention.

Fig. 5 is a plan view of Fig. 4.

50 Fig. 6 is a plan view of a templet, and holding means used.

Fig. 7 is a transverse vertical section on line 7-7 of Fig. 6.

55 Fig. 8 is a vertical section on line 8-8 of Fig. 6.

Fig. 9 is a plan view of a portion of a

bucket showing some rivet holes formed therein.

Fig. 10 is a diagrammatic elevational view of a dredge-bucket conveyer, in operative 60 position on a sand dredge.

The numeral 1 indicates a portion of a sand-dredge boat, on which is ordinarily mounted a spider or hexagonal drum 2, an endless conveyer chain 3, and a second 65 spider 4, as shown in Fig. 10. On the conveyer chain 3 are attached the buckets 5, 6, etc. The spider 2 is operated by power within the ship or sand-dredge 1, to manipulate the buckets 5, 6, etc., and thereby remove sand from the river bed 7 as is readily understood, this type of "sand-dredge" or boat being much used on some of the large rivers in recovering sand from the river bed for building and other purposes. As 70 sand is of a very gritty and hard nature the buckets 5, 6 can only be made of extremely hard material to withstand the grinding "wear", and in the present state of the art, manganese steel has been found to be practically the only useful material for this purpose, when considered from a commercial as well as a mechanical point of view. The manganese buckets 8 Fig. 1 are formed usually with an upwardly projecting lip 9 75 cast integral with the body of the bucket, so that this lip 9 takes most of the "wear" caused by contact with the sand bed 7 in digging. But even with manganese steel these lips 9 soon wear down even with, or 80 below the edges 10 of the bucket, and the whole bucket 8 has to be "scrapped" or thrown away, as it is not desirable at the present time either from a commercial or practical view point, to re-use these buckets, 85 first, because of the difficulty in cutting the extremely hard manganese steel and secondly, as rivet holes cannot be punched through said steel, in order to attach new lip portions, as might ordinarily be done were 90 the buckets of any ordinary cast or alloyed steel. Moreover, these worn manganese buckets cannot be remelted and cast over into new buckets, because the present refractories used for furnace linings will not 95 withstand the treatment from a chemical point of view. So that, as before stated, these worn manganese buckets are entirely discarded as soon as their lip portions 9 are worn down below approximately the 100 edge level 10. When it is stated, by way of illustration, that these manganese buckets

95

100

105

110

average in price, approximately twenty-five cents a pound, as against a cost of say four to six cents a pound for ordinary cast or plate steel; and that these buckets average 5 from four hundred and fifty to six hundred pounds each; the importance of being able to re-use these manganese discarded buckets is at once seen to approach a matter of great moment in this particular art.

10 Again with the above facts in mind, it is seen that if any parts of these expensive buckets can be made of less expensive material without lessening their efficiency as a whole, that improvements in the matter of 15 construction, is also very desirable. Both of these objects are attained by my invention as described herein. My method of repairing these manganese buckets, will be first described. The ordinary manganese 20 bucket is usually of a single casting, provided with integral lugs similar to 11, Fig. 3, the latter being mounted on the endless chain 3. In this case the lugs 11, the body portion 12, and the lip portion 13, are all 25 cast in one piece. By my method of repairing these buckets I stand the bucket on its end as in Figs. 4 and 5, and secure it by means of the metal housing or stand 14, and cross-bar 15, the stand 14 being rigidly secured to the foundation 16. The stand 14 30 has a top bar 40 which preferably is "machined" on its outer surfaces, and carries a slideable metal collar or casing 17 on which is rotatably mounted at 18 an oxy-acetylene 35 torch 19, having the usual supply of gas and oxygen furnished thereto, and also the cutting or burning tip 20. As shown in Fig. 5, as the bucket 8 is securely held by 15, and its attachments, and the slideable casing 17 40 can be reciprocated along bar 40, and also the torch 19 rotated about point 18, so that the lip portion 13 of the bucket can be cut along the line 21 in practically a straight line, a performance not readily attainable 45 otherwise, on account of the uncertainty of the oxy-acetylene flame when hand operated. This is practically necessary in order to have a straight edge at 21, Fig. 1, so that a butt and lap joint can be made by the new 50 lip 13 about to be attached to the body portion 12. The lip 13 is cast of manganese steel with a number of rivet holes at 22, 23, etc., and in order to form complementary rivet holes in the body portion 12 of the old 55 bucket, a templet 24 having the proper rivet spacing is mounted on the bar 40, the slideable casing 17 being moved to permit the templet to be placed in proper position over the bucket. The templet 24 has a number of 60 tubular collars 25 preferably lined at 26 with a refractory material, so as to protect the material of the bucket at 27 as much as possible when an oxy-acetylene torch tip 28 is introduced into collars 25 for burning the 65 holes 29 through the bucket material 30.

The collar 25, it will be understood, may be of considerable length, the purpose being to form a guide for the torch tip 28, and burn the hole 29 in as correct spacing location as possible. After the torch tip 28 has been 70 withdrawn, the hole 29 will appear as at 31, Fig. 9, with a somewhat uneven periphery, and while the material 30 is still in a highly heated condition, a preferably air reaming tool 32 is inserted in the collar 25, and the 75 hole 29 reamed to as nearly a perfect circle as possible. It is essential in this connection that the reaming be performed while the metal 30 is still in a heated condition, because otherwise the hard manganese steel 80 cannot be cut by an ordinary reamer. As soon as all the holes necessary have been made in the body portion 12, both on the 85 sides 33 and bottom 34, the newly cast manganese lip 13, having a shoulder at 21, and an extension at 35, to form the necessary "lap," is applied to the body portion 12, and riveted fast in the ordinary way. It is noted that the lip 12 is usually cast with the 90 holes 22-23, countersunk on the exterior, so that the rivet heads do not project into the sand when the buckets are in operation. The lip 13 is usually of thicker material in cross section than the bucket body (see Fig. 1) on account of receiving practically all the 95 "wear" contact with the sand in digging or 100 excavating.

With reference to the last stated matter it is seen that a great deal of "wear" is also carried to the joints 36, 37 of the links 11, and for this reason these links are in my invention made of manganese steel, as well as the lip 13, and in practice, even these manganese links soon wear and have elongated 105 holes at 36, 37. It is noted that this is also important in that when the links elongate materially they cannot pass over the spiders 2 and 3, Fig. 10, properly. But it is also seen that the body portion 12, comprising the two end walls 33, the rear wall 38 and 110 part of the bottom 34, receives practically very little "wear" and consequently I make this portion of ordinary cast or plate steel which can be made so much cheaper than the manganese steel portions, as before explained, that the cost of these ordinarily expensive buckets is reduced to less than half of the usual all-manganese bucket. It is seen that the links 11 have flanges 39 and 115 are riveted to the body portion 12 as shown. The bimetal bucket just described, it is seen, can be readily provided with a new wearing lip 13, by simply removing and replacing the rivets in the holes 22, 23, etc., as is 120 commonly done with other buckets at the present time.

From the above it will be seen that I have devised a new method of attaching manganese lips to worn dredge buckets whereby the latter can be re-used almost indefinitely and 130

the effect of which is practically revolutionary in this particular art; and secondly, I have provided in an article of manufacture, a new type of bi-metal bucket having the 5 "wearing" portions of extremely hard material adapted to withstand severe service, and having the remaining portion of said bucket constructed of comparatively softer and less durable material without detracting 10 from the efficiency and utility of the dredge bucket as a whole.

What I claim is:—

1. A method of attaching lips to dredge-buckets which consists in first removing the 15 worn lip portion of said buckets and piercing holes in the edge of the bucket adjacent to the line of severance, reaming said holes while the material is in a heated condition, and then riveting a new lip portion on said 20 bucket.
2. A method of attaching new lips to worn manganese dredge buckets which consists in first removing the worn lip portion of said bucket and piercing rivet holes in the edge 25 of the bucket adjacent to the line of severance by using an oxy-acetylene tool in conjunction with means for maintaining the alinement of said tool in the cutting and piercing operations; and then riveting a cutting-lip portion on said bucket.
- 30 3. A method of repairing worn manganese

dredge-buckets which consists in cutting away the worn lip portion by using an oxy-acetylene torch, rotatably mounted on a reciprocating means for holding said torch in 35 proper alinement during the cutting operation; piercing rivet holes in the edge of said buckets with said torch, while same is held in proper position by a spacing and direction means; reaming said rivet holes while 40 the bucket material is in a heated condition, with a reaming tool held in proper position by the aforesaid spacing means; and then riveting a cutting-lip portion on said bucket.

4. A method of repairing worn manganese 45 dredge-buckets, which consists in cutting away the worn lip portion with an oxy-acetylene torch rotatably and reciprocally mounted on a lineal alining stand; piercing rivet holes in said bucket with said torch 50 used in conjunction with a spacing means having a collar adapted to control the size and direction of the torch flame; reaming said rivet holes while the bucket material is in a heated condition, and then attaching 55 a cutting-lip portion on said dredge-bucket.

In testimony whereof I affix my signature.
